UNITED STATES PATENT OFFICE.

ENOCH NORRBOM, OF BROOKLYN, NEW YORK.

GAS-ENGINE.

1,281,196.

Specification of Letters Patent. Patented Oct. 8, 1918.

Application filed July 20, 1917. Serial No. 181,743.

To all whom it may concern:

Be it known that I, ENOCH NORRBOM, a citizen of the United States, and a resident of the city of New York, borough of Brooklyn, in the county of Kings and State of New York, have invented a new and Improved Gas-Engine, of which the following is a full, clear, and exact description.

This invention relates to internal combustion engines and has particular reference to improved facilities for more thoroughly purging the cylinder than is ordinarily customary. More definitely stated I provide a means in connection with the piston whereby a charge of fresh air is taken from or through the crank casing at each up-stroke of the piston and on the succeeding down stroke such charge of fresh air is compressed and delivered into the main cylinder so that on the exhaust stroke said charge of fresh air serves to cleanse or purge the cylinder.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical sectional view on the line 1—1 of Fig. 2; and

Fig. 2 is a similar view on the line 2—2 of Fig. 1.

10 represents a crank casing having a breather 11 of any well known form associated therewith through which fresh air is admitted into the crank casing. The crank shaft 12 is journaled in the casing as usual and has connected thereto a connecting rod 13 having at its upper end a T-head 14.

The piston 15 reciprocates for the usual purposes in the cylinder 16, but is peculiar in having a downwardly projecting tubular cylinder extension 17 having a smooth outer surface acting as a piston in a cylindrical boss 18 constituting a part of a base plate 19 anchored between the lower end of the cylinder 16 and the top flange 20 of the crank casing. The piston is centrally tapped at 21 to receive the threaded shank 22 of a two part anchor block 23 fitted into the interior of the extension 17. This block consists of two substantially equal parts, the only dif-

ference being that one is countersunk at 24 for the head of a binding screw 25 extending therethrough into the other block part. These block elements are provided with transverse registering bearing holes 26 into which the ends of the T-head 14 project, the T-head being cylindrical and rocking in the bearing holes in accordance with the rotation of the crank. The lower ends of the block elements are cut away at 27 to provide a clearance for the upper end of the connecting rod while making its oscillation in the block 23. In assembling these parts the block elements are slipped upon the ends of the head 14 and clamped together by the screw 25. The anchor block is then projected into its place in the piston and relative rotation between the piston and the anchor block is then set up to tighten the block in the piston, the conical surface of the anchor block acting to wedge or bind snugly into the piston as a result of the action of the threaded shank 22.

The construction of the cylinder and associated parts is such as to provide as large a cavity as possible at 28 below the piston into which a charge of fresh air is sucked from the crank casing through the opening 29 in the boss 18, the air passing thence laterally through one or more ports 30 leading into said cavity 28 just as the piston is completing its up-stroke, this inflow of air into the cavity 28 being insured by the vacuum formed by the up-stroke of the piston. When the piston makes its next down-stroke the extension 17 promptly closes and seals the ports 30 and the piston compresses the air trapped within the cavity 28. When the piston, however, approaches the limit of its down-stroke as indicated in dotted lines in Fig. 2 the air trapped and compressed below the piston spouts forcibly from the lower end of the cavity 28 out through one or more ducts 31 into the cylinder above the piston. If now the exhaust port 32 is open the spouting of the fresh air in this manner into the bottom of the active portion of the cylinder will thoroughly purge the exhaust gases therefrom. During the subsequent reciprocations of the piston this admission of fresh air into the cavity 28 and the delivery thereof into the active portion of the cylinder will be repeated. With respect to the admission of fuel gases through the inlet port 33 it will be understood that such gases will be sufficiently rich to justify the dilution

incident to the mixture with such fresh air just prior to the compression stroke of the piston.

An engine built in accordance with this disclosure is a relatively simple and cheap construction and easy to assemble and serves to increase the efficiency of the device materially because of the utilization of the fresh air in the ways above indicated.

10 I claim:

In a gas engine, the combination of a cylinder, a crank casing, means to connect the crank casing to the cylinder, an annular base plate secured in the lower end of the cylinder at the place of connection between the casing and the cylinder, said plate hav-

ing a central hollow cylindrical boss having a lateral port therethrough to bring the crank casing into communication with the lower portion of the cylinder, a piston in 20 the cylinder and having a cylindrical projection fitted as a piston in said boss, said projection uncovering said lateral port when the piston is up and sealing said port when the piston is down and a duct leading from 25 the lower end of the cylinder to a point farther up whereby the air trapped within the lower end of the cylinder and compressed by the piston on its down stroke will be delivered into the cylinder above the piston.

ENOCK NORRBOM.
